J. VOSS

SAFETY DEPOSIT BOX

Filed June 22, 1922

Fig. 1.

By Marklinney & Marklinney
Attorneys

UNITED STATES PATENT OFFICE.

JOSEPH VOSS, OF MANITOWOC, WISCONSIN.

SAFETY DEPOSIT BOX.

Application filed June 22, 1922. Serial No. 570,063.

To all whom it may concern:

Be it known that I, JOSEPH Voss, a citizen of the United States of America, residing at Manitowoc, in the county of Manitowoc and

5 State of Wisconsin, have invented certain new and useful Improvements in Safety Deposit Boxes, of which the following is a specification.

The present invention relates to safety deposit boxes, and more particularly to the construction of the same for preventing unauthorized opening of the box.

An object of the present invention is to provide a safety deposit box which is constructed to resist crushing by blows of a sledge or other heavy tool and also to resist opening by prying or when subjected to drilling, or other various means commonly employed for breaking into devices of this

20 character.

Another object of the invention is to provide a safety deposit box with the usual hinged door or lid, and the usual duplex lock which has a sliding bolt, adapted to engage a keeper formed by a recess in the inner wall of the box; and to equip such box structure with a supplemental locking means which may be controlled by manipulation of the first lock, and with cooperating parts 25 built into the box structure for supporting the second locking means for not only holding the door or lid against being pried open, but also against being collapsed or forced inwardly under heavy blows or pressure.

30 A further object of the invention is to provide a relatively simple attachment for safety deposit boxes which may readily be applied to boxes of common construction and which occupies but small space in the box and does not alter exterior configuration and dimensions of the box, so that the latter may be used in the ordinary safety deposit vaults of banks and other institutions and places where money and other valuable articles are to be protected.

35 With the foregoing and other objects in view, the invention will be more fully described hereinafter, and will be more particularly pointed out in the claims appended hereto.

In the drawings, wherein like symbols refer to like or corresponding parts throughout the several views.

40 Fig. 1, is a horizontal longitudinal section taken through a safety deposit box constructed according to the present invention,

the lid or cover being shown in a partly open position and the dotted lines showing the paths of travel of the various parts of the supplemental locking attachment of this invention.

45 Fig. 2, is a vertical section taken through the same looking in the direction of the arrows and on the line 2—2 of Fig. 1.

Fig. 3, is a longitudinal section through the forward end of the box taken substantially on the line 3—3 of Fig. 2, and

50 Fig. 4, is a fragmentary horizontal section taken through the forward portion of the box showing the cover in closed position.

55 Referring to the drawing, the present invention is illustrated as applied to a safety deposit box of substantially rectangular configuration and which has a rear wall 10, side walls 11 and 12, and top and bottom walls 13 and 14. These various walls may be made in any suitable or well known manner to provide an impenetrable enclosure open only at its front end. The front end of the box is provided with a door or lid 15 which preferably fits in between the front edge portions of the side and top and bottom walls, and which is adapted at its outer surface to lie flush with the front edge of the box so that prying or other tampering with the door

80 may be offset to a large extent. The door 15 is mounted upon a vertical pivot shaft 16 which is placed in the side wall 12, and which terminates within the top and bottom walls 13 and 14 to prevent the driving of the

85 pivot 16 out of place. The free end of the door 15 has, in its outer edge, an undercut recess forming a stop or lip 17 adapted to fit into a correspondingly shaped concavity or shoulder 18 formed in the front edge of

90 the side wall 11. To provide a suitable bearing surface, the shoulder 18 is formed in part by a vertical bar 19 which is provided in the outer edge of the side wall 11 at the inner face thereof, and which is arranged in

95 substantially the same position and manner as is the pivot 16 located at the opposite side of the box.

100 Safety deposit boxes of this type are usually provided with a duplex lock 20 having a key slot 21 for a master key, and a second key slot 22 for an individual key, the lock being of the duplex type so that operation of both of these keys is essential to the retraction of the bolt 23 of the lock.

105 The side wall 11 of the box is provided with a keeper 24 in the form of a cavity or recess

provided in the inner face of the wall 11 and designed to register with the bolt 23 when the door 15 is closed. In locked position the bolt 23 projects into the keeper 24 and behind the bar 19, and the thickness of the metal of the wall 11 beneath the bar 19 so that the bolt is securely held from being forced outwardly by mutilating the wall 11, or otherwise being released. The lock 20 is usually secured to the inner side of the door or lid 15 by machine screws or the like. In the present instance machine screws 24 are used, which pass through the lock 20 and which are threaded into the lid 15, the screws being provided near their outer ends with shoulders 25 which bear against the inner side of the lock 20 and bind it to the door 15. The shoulders 25 provide guides 26 upon which is slidably mounted a locking plate 27 having a slot 28 for each guide 26. The shoulders or guides 26 of the bolts have heads 29 on their outer ends in the form of bolt heads having the usual angularly disposed faces for receiving a wrench or other suitable tool for turning the machine screws 24. The locking plate 27 is adapted to slide against the inner side of the lock 20 and beneath the heads 29 of the screws 24 within the limits of the slots 28. As shown best in Fig. 2 and 3 the plate 27 is of a width equal substantially to the height of the interior of the box, and the plate 27 is left its full width at the free end of the door to provide a locking lip 30 of the full width of the plate, the lip 30 being adapted to engage in a vertical groove or recess 31 formed across the inner wall of the side wall 11.

The locking plate 27 is provided with one or more recesses 32 in its top and bottom edges adapted to register with and receive therethrough correspondingly shaped stops or abutments 33 which are welded or otherwise permanently attached to the inner faces of the walls 13 and 14 of the box. The stops 33 are so located upon the top and bottom of the box that they register with the recesses 32 only when the locking plate 27 is retracted. When the locking plate is projected outwardly into locking position the recesses 32 are moved out of register with the stops 33, and consequently the intermediate portions of the plate 27 are brought into position behind the stops 33 and the latter prevent any outward movement of the plate.

The plate 27 is provided, at a suitable point, with a slot 34 which receives a pin 35 mounted on a movable part of the lock mechanism, and in the present instance is mounted on and movable with the bolt 23, and which is adapted to be operated upon the projection and retraction of the bolt for shifting the plate 27 into locking and releasing positions.

The locking plate 27, when the door 15

is closed, supported throughout its length upon ledges 36 which may be in the form of steel plates welded or otherwise suitably and permanently fitted to the inner faces of the top and bottom walls 13 and 14 and with their outer edges flush with the inner wall of the lip-receiving recess 31. The plate 27 when closed is supported against these ledges 36, and consequently any pressure or impact upon the door 15 is resisted not only by the lip 17 but also by these relatively large and strong ledges. As the door 15 swings into open and closed positions upon the pivot 16 at one end of the box, the recesses 32 in the edges of the locking plate, which are preferably provided with at least one curved wall 37, receive therethrough the stops 33 which are also provided with at least one correspondingly curved wall 38 so that the locking plate may be freely and easily swung into closed and open positions with the cover 15, and maintain a relatively tight fit at all times.

I have illustrated and described a preferred and satisfactory embodiment of my invention, but it is obvious that changes may be made therein within the spirit and scope thereof as defined in the appended claims.

What is claimed is:

1. In combination with a safety deposit box having a door and a lock secured to the inner side of the door, a sliding plate mounted on the inner face of the lock, a connection between the plate and a movable portion of the lock mechanism whereby the locking plate may be moved into projected and retracted positions upon the opening and closing of the lock, said plate having recesses in the lateral portions thereof, and stops secured to the inner faces of the box in position to aline with the recesses of the plate when the latter is retracted and adapted to be out of line with the recesses when the plate is projected, whereby said stops are adapted to engage the intermediate portions of the plate to prevent opening of the door.

2. In combination with a safety deposit box having a hinged door adapted to close in flushed relation with the outer edge of the box, and a lock secured to the inner side of the cover, a plate slidably mounted against the inner side of the lock and being of a width equal substantially to the height of the interior of the box, means connecting said plate to a movable portion of the lock mechanism for cooperatively opening and closing the plate and the lock, said plate having recesses in its longitudinal edges, abutments secured to the inner opposite faces of the box outwardly of the plane of the sliding plate when the door is closed and arranged in position to aline with the recesses in the plate only when said plate is retracted, a wall of the box having a

groove therein adapted to receive the outer edge of the plate when projected, and ledges secured within the lower portion of the box inwardly of said plate for supporting said plate, lock and cover when closed in position under exterior pressure and impact.

3. In combination with a safety deposit box having a hinged door and a lock on the inner side of the door, a slotted plate fitted against the inner side of the lock, shouldered machine screws fitting in the slots of the plate and projecting into the lock and door for holding the parts as-

sembled and for guiding the plate in its movements of projection and retraction, said plate having spaced apart recesses in its longitudinal edges, stops secured to the inner opposite walls of the box in position to register with the recesses when the plate is retracted, and ledges secured to the inner opposite walls of the box for supporting said plate when the door is closed.

In testimony whereof I affix my signature.

JOSEPH VOSS.
